UNITED STATES PATENT OFFICE

2,430,030

INSERTABLE CLOTHES HOLDER FOR HAND CARRIED LUGGAGE

John Riess, St. Louis, Mo., assignor to Henry Hotze & Sons Company, a corporation of Missouri

Application August 18, 1944, Serial No. 550,105

2 Claims. (Cl. 223—85)

1

This invention relates to that class of clothes holders for use in hand carried luggage or the like, on which the clothes of the wearer or traveler are hung and folded, ready for insertion within the luggage and in fact its use primarily is in combination with the luggage or bag.

An object of the invention therefore, is to provide a holder for clothes or wearing apparel, which are hung or dressed on the holder and are secured in their dressed positions on the holder, ready for bag insertion.

Another object is to provide a clothes holder with improved foldable and slotted parts for sustaining the clothes in their dressed positions.

A further object is to provide a clothes holder of an improved construction and with simplified means thereon whereby to self-direct the manner in which the clothes are to be secured or draped on the holder.

A still further object is to provide a traveler's clothes holder, particularly for male attire, of an improved construction whereby shifting displacement of the holder secured apparel is eliminated.

Other objects and advantages will appear as this description progresses and by reference to the drawing, in which:

Figure 1 is a side elevation of this improved clothes holder showing the manner in which it is inserted and engaged in hand carried luggage, and the luggage being shown in dotted lines.

Figure 2 is an enlarged perspective view of the clothes holder showing the securing flap thereof in outwardly swung position.

Figure 3 is an enlarged transverse vertical section taken approximately on line 3—3 on Fig. 2.

Figure 4 is an enlarged longitudinal horizontal section taken approximately on the line 4—4 of Fig. 1.

Figure 5 is an enlarged transverse section taken approximately on the line 5—5 of Fig. 4.

Referring by numeral to the accompanying drawing this improved clothes holder comprises a rectangular frame 6 having top and bottom longitudinally disposed bars 7 and 8 respectively and respective end members 9 and 10 disposed at right angles to the bars 7 and 8. Disposed and secured to one side of the bars 7 and 8 is a wall 11 and secured to the other side of the top bar 7 at 14 and hinged thereto at 12 is a flap 13 which is of the approximate size of the wall 11 and fastened to the part 14 at the approximate center of its length, is one end of a strap 15, for the support of a hanger 16.

Each of the end members 9 and 10 is provided

2

with an elongated slot 17, said slots being in alignment and are disposed on one side of the wall 11 with their inner edges flush therewith and specifically on the flap side of the frame to form a pocket 18 between the wall 11 and the flap 13 when the flap is in closed position in the manner as shown in Fig. 3.

In the order of dressing or draping a two-trouser suit of male attire on the holder which is done entirely outside of the hand carried luggage or bag 19, the holder is flatly disposed on a table or the like and the pocket 18 uppermost with the flap 13 swung away, and in this position the trousers A being properly folded, has the legs

10 15 20 thereof inserted and pulled through the slot 17 of the end member 9 of the frame 6 and are inwardly pulled a suitable distance within the pocket 18 on the wall 11. The folded legs 21 of the extra pair of trousers B are then inserted and 20 pulled through the slot 17 of the end member 10 of the frame 5, to a suitable distance in the pocket 18 and brought to rest on the legs 20 of the trousers A. The waist portion 22 of the trousers A is then swung over the upper disposed edge 23 25 of the end member 9 and folded on the legs 21 of the trousers B and subsequently the waist portion 24 of the trousers B is swung over the upper disposed edge 25 of the end member 10 and folded and rested on the waist portion 22 of the 30 trousers A as clearly shown in Figs. 4 and 5.

The coat C and vest, if any, is then folded on the hanger 16 with the opening or buttoned portions thereof against the flap 13 and as the coat ordinarily is longer than the depth of the flap 13, 35 said flap when layed on top or against the folded trousers provides for the folding of the depending length of the coat around the bottom bar 8 of the frame 6 and upon turning over the holder or frame with the flap 13 at the bottom, 40 the lower portion 26 of the coat is folded into the space or pocket 27 against the wall 11 on the other side of the pocket 18.

For holding the tail or lower portion 26 of the coat C in the pocket 27 a strap 28 is provided, 45 said strap comprising two parts, each being secured to respective end members 9 and 10 at 29 and are fastened to each other by the buckle 30.

After the wearing apparel A, B and C has been dressed and folded on and in the holder in the 50 manner described and shown in Figs. 4 and 5 and the holder is deposited in the luggage bag 19 in the upright position shown in Fig. 1, transporting use of the luggage will not effect or disarrange the holder arranged wearing apparel.

Presumably, the luggage bag will contain side

disposed pockets or the like for other useable essentials of the traveler and in practice and use of this improved holder, it may be found preferable to deposit the holder in the bag as a last essential.

In the use of a clothes holder of this improved character, if the clothes are properly arranged therein in the manner described, transportation use of the luggage or bag can not in any way disturb the folded wearing apparel and if desired the user may retain the apparel in the holder until use thereof is required. Also, it is obvious that the dressing and arranging of wearing apparel in this improved holder is much simpler and more adequate than in the old manner of folding and arranging a suit of clothes inside of a luggage bag.

While I have described one embodiment of my invention with some particularity, obviously many other embodiments thereof may occur to those skilled in the art to which it appertains. I, therefore, do not limit myself to the precise details described, but claim as my invention all variations and modifications coming within the scope of the subjoined claims.

What I claim is:

1. A clothes holder comprising a frame having vertically disposed end members, a partition

wall secured between said end members intermediate their width to provide a spacing on each side of the partition wall, each of said end members having an elongated opening therein on one side of said partition wall for trouser leg insertion, a flap member swingably secured to said frame on the elongated opening side thereof, and garment hanging means on said flap member.

2. A clothes holder comprising a frame having vertically extending end members, a partition wall secured between said end members intermediate their width to provide a spacing on each side of the partition wall, each of said end members having an elongated opening therein on one side of said partition wall for trouser leg insertion, a flap member swingably secured to said frame, and coat hanging means on said flap member.

JOHN RIESS.
